DIRECTED ISOMER FORMATION IN THE OXO REACTION

Hugh J. Hagemeyer, Jr., and David C. Hull, Longview, Tex., assignors to Eastman Kodak Company, Rochester, N. Y., a corporation of New Jersey

Application March 29, 1954, Serial No. 419,145

5 Claims. (Cl. 260—604)

This application is a continuation-in-part of our earlier applications Serial No. 22,716, filed April 22, 1948, now Patent No. 2,694,734, issued November 16, 1954 and Serial No. 131,499, filed December 6, 1949 (a continuation-in-part of said Serial No. 22,716 and of our now abandoned application Serial No. 78,938, filed March 1, 1949), now Patent No. 2,694,735 issued November 16, 1954.

This invention is concerned with the production of oxygenated compounds and more particularly with the production of valuable carbonyl compounds such as aldehydes by the reaction of an olefinic compound with carbon monoxide and hydrogen. It is specifically concerned with a process for carrying out the reaction of olefins with carbon monoxide and hydrogen under conditions which favor the formation of a single isomer. It is further concerned with the reaction of an olefin with carbon monoxide and hydrogen in the presence of one of the aldehyde isomers formed as a product of the reaction in order to suppress further formation of that isomer. It is further specifically concerned with the reaction of ethylene with carbon monoxide and hydrogen under conditions such that the formation of diethyl ketone is suppressed. It is further concerned with a process for reacting olefins including propylene and higher olefins in the presence of a suitable acetal and water whereby the formation of one or the other of the possible isomeric aldehydes is suppressed. The invention is generally concerned with methods of controlling the ratio of normal to isovaldehyde formed in the oxonation of olefins. It is specifically concerned with processes wherein the oxonation of olefins is carried out in the presence of particular aldehydes, acetals, and/or ketones, and alcohols. The objects of the invention are directed to these reactions.

Prior art methods and solvents used for carrying out the reaction of carbon monoxide and hydrogen with olefins and olefinic compounds result in the formation of both normal and isovaldehydes and usually in the ratio of 1:1 to 1.5:1. The oxonation of the lower aliphatic olefins, ethylene and propylene, also results in the formation of substantial quantities of diethyl ketone and the mixed dipropyl ketones, respectively. During our study of the oxo process we have discovered several new and unpredictable methods of operation which can be used to control the ratio of normal to isovaldehyde produced, and also to suppress the formation of ketones.

In normal operation the reaction of ethylene or propylene with carbon monoxide and hydrogen can be represented by the following equation:

where R is hydrogen, alkyl, or aryl.

The ketones formed according to Reaction 2 are present in amounts up to 30% of the weight of the product in the batchwise operation. We have found that by recycling this or an equilibrium amount of ketone in batchwise operation the further formation of the ketone can

be suppressed. In continuous operation the formation of ketone is somewhat less and usually in the range of 5-10%, and the further formation of ketone is completely suppressed by maintaining this concentration of ketone in the medium in the reactor space.

The oxonation of olefins, including propylene and above with a source of carbon monoxide and hydrogen results in the formation of a mixture of normal and isovaldehydes according to the equations:

10 Straight chain or normal aldehyde formation:

Alpha methyl or isovaldehyde formation:

where R is hydrogen, alkyl, or aryl.

If the reaction is carried out in the presence of a standard cobalt-thoria-magnesia catalyst suspended in ethers, alcohols, and hydrocarbons, or in the presence of soluble cobalt catalysts such as solutions of cobalt carbonyl in butanol, toluene, diethyl ether, or the olefin itself, a 50:50 plus or minus 10 mixture of normal and isovaldehydes is recovered. We have now discovered an unusual and novel method by which it is possible to direct the isomer formation to favor either straight chain or normal butyraldehyde formation to the exclusion of the alpha methyl or isovaldehyde formation, or vice versa. In fact, it is possible to operate under conditions disclosed and discovered by us so that one or the other of the aldehyde isomers can be suppressed completely.

We have discovered four methods of operation by which we can direct the isomer formation in the oxo process.

In the first method of directing isomer formations in the oxo process, we have found that by recycling one of the isomeric aldehyde products, the further formation of that particular isomer can be suppressed, and by operating in the presence of a large excess of that isomer, the further formation of the isomer can be eliminated entirely.

40 Still another application of this particular method is the suppression of the further formation of diethyl ketone and dipropyl ketone in the oxonation of ethylene and propylene by recycling a substantial portion of that ketone to the reactor space.

45 The second method of directing isomer formation in the oxo reaction is to carry out the oxonation of the olefin in the presence of an acetal of that isomer which it is desired to suppress or eliminate. In addition to the acetal the reactor space usually contains 1-10% water, and under these conditions the acetal exists in equilibrium with the free aldehyde. The equilibrium concentration of free aldehyde functions as in Method 1 to suppress further formation of that particular isomer.

50 The third method of directing isomer formation in the oxo reaction takes advantage of the difference in the rate of acetal formation of normal and isovaldehydes. This is done by operating in a solvent composed predominantly of a primary or secondary alcohol and under these conditions the rate of formation of the acetal of the normal isomer to that of the isovaldehyde is approximately 5-10 times greater. For example, the reaction of normal butyraldehyde with butyl alcohol to form dibutyl butal is 10 times faster than the reaction of isobutyraldehyde with normal butyl alcohol to form dibutyl isobutal. This

55 in effect maintains reaction conditions wherein an excess of the isovaldehyde is present and thus the formation of the normal isomer predominates. By maintaining a high concentration of alcohol in the reactor space, it is possible to change the normal to isovaldehyde ratio from the normal 50:50 plus or minus 10 to a ratio of 4-6 to 1.

The fourth method of directing isomer formation in the oxo reaction is that previously described in our appli-

cation Serial No. 22,716 wherein the reaction of an olefin with carbon monoxide and hydrogen is carried out in the presence of a lower aliphatic ketone. This is a completely unexpected result and although we can offer no explanation of why the ketone exerts such an effect on the oxo reaction, we have found that the formation of the normal isomer predominates.

Although metallo-hydrocarbons and ketones are known to favor abnormal additions in certain reactions, that is the formation of normal compounds, we are aware of no prior art relating to the use of aldehydes, acetals, alcohols, and/or ketones as a method of directing isomer formation in the oxo process. It must be remembered that the novelty in this process resides in the method and the concentration of aldehydes, acetals, alcohols, and/or ketones maintained in the reactor space rather than the simple fact of carrying out the oxo reaction in the presence of a solvent selected from one of these classes. Thus, although it is true that acetals and alcohols have previously been mentioned as components in oxo solvents, no one has ever deliberately used these solvents according to the method of our invention in order to control and/or direct isomer formation in the oxo process.

In the process of the present invention an olefin or an olefinic compound and a source of carbon monoxide and hydrogen are reacted in the presence of a solution and/or suspension of a suitable cobalt catalyst or mixed cobalt-iron catalyst. The reaction is carried out at temperatures ranging from 75-200° C., usually in the range of 130-175° C., and at 40-700 atmospheres. Typical catalysts which may be used include a reduced cobalt catalyst composed of 25-45% cobalt, 2% thoria, 2% magnesia, and the remainder kieselguhr, and 40-70% reduced or other similar solid catalysts suspended in the desired reactor composition. We have further found that the same results may be obtained when the reaction is carried out in the presence of a solution of cobalt carbonyl. The actual mechanics of the present invention are perhaps best illustrated by the following examples, with regard to the first of which we have attached a drawing showing a plot of added aldehyde type and concentration against percent n-butyraldehyde in the product.

EXAMPLE 1

A series of runs was made wherein propylene was reacted with carbon monoxide and hydrogen in the presence of iso or normal butyraldehyde and 20 g. of a 36% cobalt, 2% thoria, 2% magnesia on kieselguhr catalyst, 62% reduced and suspended in 190 g. of normal butyl alcohol, 10 g. water. All the runs were carried out at 2,000-3,000 p. s. i. and at temperatures ranging from 130-150° C. The reaction rates varied from 20.3 to 32.8 gram moles per liter of reaction space per hour. Two gram moles of propylene were reacted in each run and at the end of the run the autoclave was emptied, the crude product filtered and distilled from an equal volume of 1% sulfuric acid solution. The iso and normal butyraldehydes were recovered as the azeotropes. The results are tabulated in Table I which reports the percent added aldehyde in the total aldehyde product and also the percent normal butyraldehyde produced.

Table I

PERCENT ADDED ALDEHYDE IN TOTAL ALDEHYDE PRODUCT

Run No.	n-HBu	Iso-HBu	Percent n-HBu Produced
1			66.6
2		33.8	87.0
3		20.4	73.0
4	21.2		26.9
5	47.3		12.5
6		23.0	73.0
7		32.0	82.2
8		10.0	63.2

For purposes of convenience these results are also plotted in Figure 1. It is interesting to note that the relationship between the percent added aldehyde and the total aldehyde produced and the percent normal butyraldehyde produced is almost a straight line relationship.

EXAMPLE 2

One hundred grams of the aldol trimer formed by the aldol condensation of isobutyraldehyde, 10 g. of water, 10 20 g. reduced oxo catalyst described in Example 1, and 190 g. of normal butyl alcohol were charged to a 1-liter stainless steel rocking autoclave. Two gram moles of propylene were reacted with an equimole mixture of carbon monoxide and hydrogen at 130-138° C. and at 15 pressures ranging from 2,100-3,000 p. s. i. The reaction rate was 19.4 gram moles per hour and the aldehyde produced by the oxo reaction was all normal butyraldehyde.

The aldol condensation was carried out as follows: 20 216 grams of isobutyraldehyde and 20 grams of 28% sodium hydroxide were fed to a continuous aldol reactor over a 2 hour period. The reaction temperature was held at 5-10° C. by cooling as required. The product was neutralized with acetic acid to pH=6, decanted, 25 washed with water, decanted and distilled at reduced pressure. One hundred ninety-two grams of the isobutyraldehyde hemiacetal of isobutyraldol were obtained.

EXAMPLE 3

35 Fifty grams of para-isobutyraldehyde, 2 g. of water, 20 g. of reduced oxo catalyst as described in Example 1, and 190 g. of normal butyl alcohol were charged to a 1-liter stainless steel autoclave. Two gram moles of propylene were reacted at 130-145° C. with pressures 40 ranging from 2,000-3,000 p. s. i. A reaction rate of 19.0 g. moles per hour was observed. Azeotropic distillation of the aldehydes from a 1% solution of sulfuric acid in water showed that 85% of the aldehydes produced were normal or the ratio of normal to isobutyraldehyde produced was 5.7:1.

45 Examples 2 and 3 show that sources of isobutyraldehyde other than monomeric isobutyraldehyde produce the same results. Apparently the aldol trimer and the para aldehyde trimer break down under oxo condition. The use of the trimers is particularly valuable in continuous 50 operation since a high throughput and high rate of reaction for a given reactor space make it desirable to keep the partial pressures due to the reactor liquid compositions as low as possible.

EXAMPLE 4

Two hundred grams of normal propyl alcohol, 10 g. of water, and 20 g. of reduced oxo catalyst as described in Example 1 were charged to a 1-liter stainless steel autoclave. Ethylene was reacted with carbon monoxide and hydrogen at 140-153° C. and at 2,300-3,200 p. s. i. After two gram moles of ethylene had been reacted, the crude reaction product was filtered and charged to a still with an equal volume of 1% of sulfuric acid and water. Distillation gave 24 g. of propionaldehyde, 7.5 g. of diethyl ketone and 3 g. of propyl alcohol.

In a second run employing 190 g. of propyl alcohol, 10 g. of diethyl ketone, 10 g. of water, and 20 g. of reduced oxo catalyst, two gram moles of ethylene were 70 oxonated at 135-148° C. and at pressures ranging from 2100-3000 p. s. i. The crude reaction product was filtered and charged to a still with an equal volume of 1% sulfuric acid and water. Distillation gave 77 g. of propionaldehyde, 9.6 g. of diethyl ketone. A comparison of the two runs shows that by incorporating a small amount of diethyl ketone in the initial charge to the

autoclave the further formation of this ketone was completely suppressed.

EXAMPLE 5

A continuous oxo reactor 9" inner diameter and 20' high was charged with 30 gallons of propyl alcohol containing 10 weight percent of a cobalt-thoria-magnesia oxo catalyst 60% reduced. Ethylene, carbon monoxide, and hydrogen were fed continuously through the reactor and unreacted gases were continually cycled through the reactor by a compressor. The ethylene concentration in the reactor space was maintained between 10-18%, the carbon monoxide concentration between 20-35% with the residual gas being hydrogen and a small amount of inerts. During one period of operation a total of 16,890 pounds of propionaldehyde was produced with an over-all yield from ethylene of 75.2%. In this operation the propionaldehyde was distilled out as formed together with substantial amounts of the azeotropes of diethyl ketone, propanol, and dipropyl propional. The crude product from the reactor was stripped of propionaldehyde, and the residual material including diethyl ketone, ethyl alcohol, and dipropyl propional was recycled to the reactor continuously. In this same period the total yield or production of diethyl ketone was only 290 pounds. It can be assumed that most of the diethyl ketone was produced in the first several days of operation.

In a second period of operation a total of 13,277 pounds of propionaldehyde was produced with an over-all yield from ethylene of 77%. During this same period, in which the diethyl ketone produced in the previous period was continuously recycled to the reactor, there was no increase in the inventory of diethyl ketone.

The above examples show that both in the batchwise and continuous oxonation of ethylene the formation of diethyl ketone can be completely suppressed by maintaining a concentration of this ketone in the reactor space. The concentration required varies with temperature, pressure, catalyst activity and reactor liquid composition. Under the oxonation conditions used in the above runs, a diethyl ketone concentration of 5-10 percent in the reactor space is sufficient.

EXAMPLE 6

Runs 1-4 (below) show the effect of using the butals of normal butyraldehyde and isobutyraldehyde on the formation of aldehyde isomers in the oxonation of propylene. In each run two gram moles of propylene were oxonated at temperatures ranging from 130-155° C. and pressures of 2100-3000 p. s. i. The reaction rates averaged 13.8-22.4 gram moles per hour per liter of reactor space. In each run 190 g. of a butal, 10 g. of water, and 20 g. of reduced oxo catalyst were charged to an autoclave of 1-liter capacity. Run 3 was a check run employing butyl alcohol as the solvent. These runs are summarized in Table II.

Table II

Run	Medium	Percent n-HBu Produced	Ratio n- to iso-HBu
1	Dibutyl isobutal	93	13.3/1
2	Dibutyl n-butal	56.5	1.3/1
3	Butanol	66.6	2/1
4	Dibutyl isobutal	85.5	6.2/1

From the above results it can be seen that under oxonation conditions and in the presence of water an equilibrium is set up between the butal and the aldehyde. This is simply another method of furnishing one or the other of the butyraldehyde isomers to the catalyst suspension medium in order to suppress further formation of that particular isomer.

The oxonation of a 2 gram mole charge of propylene in 190 g. of butanol, 10 g. of water, and with 20 g. of re-

duced oxo catalyst usually results in the formation of normal and isobutyraldehyde in the ratio of 2:1, as shown in Run 3, Example 6, above.

EXAMPLE 7

In the continuous production of butyraldehydes a reactor 20' high and 9" inner diameter and containing 30 alternating partial plates was charged with a slurry of 30 pounds of solid catalyst with a composition of 38% cobalt, 2% thoria, 2% magnesia, 58% Supercel, and 64% reduced in 20 gallons of butyl alcohol. The catalyst slurry was heated to 120° by cycling a feed gas rich in hydrogen through a preheater and then through the catalyst slurry in the reactor. Propylene was pumped in gradually to the recycle gas stream immediately before the preheater and the exothermic reaction was allowed to bring the temperature in the reactor to 140-170° C. This temperature was maintained by controlling the temperature of the incoming recycle gas and by distilling out the aldehyde as formed. Although the reaction was started with pure butyl alcohol containing 3-5% water, there was a wide variation in the reactor liquid composition due to the formation of high boilers. The high boilers are comprised mainly of butals. In continuous operation a crude product containing from 15-45% butyraldehydes is distilled off continuously, depressurized, and pumped to a distillation system. After stripping out the aldehyde azeotropes, the remainder is recycled to the reactor to maintain a reactor level. Operating in this manner the only butyl alcohol fed to the reactor is that used to slurry make-up catalyst. As a result the reactor liquid composition is generally comprised of 5-10% butyl alcohol, 75-80% mixed butals, and 10-15% unidentified high boilers. The rate of production of this unit was stabilized at 1200-1500 pounds per day of mixed butyraldehydes and the ratio of normal to isobutyraldehyde averaged 1.65:1. This operation is discussed in greater detail in our application Serial No. 318,888, filed November 5, 1952, as a continuation-in-part of the above-mentioned application Serial No. 78,938, said application Serial No. 318,888 having issued as Patent No. 2,748,167 on May 29, 1956.

In an alternate method of operation the crude product distilled from the reactor is depressurized, and pumped to a distillation system, stripped of the butyraldehyde azeotropes, and a portion of the residual reactor liquid is led to a hydrolysis column containing 1% sulfuric acid in water wherein the butals are hydrolyzed to recover butyraldehydes and butyl alcohol. In this manner the butyl alcohol content of the reactor liquid can be increased by feeding butyl alcohol as well as butals for make-up liquid. We found that the ratio of normal to isobutyraldehyde produced varied directly with the percent butyl alcohol maintained in the reactor liquid. The results for several periods of operation wherein substantial quantities of mixed aldehydes were produced while maintaining set limits of butyl alcohol concentration in the reactor space are listed in Table III.

Table III

Percent BuOH in Reactor Liquid	Total Aldehydes Produced in Pounds	Average Ratio of n- to iso-HBu
5-10	123,600	1.65
10-20	112,100	1.92
20-40	69,320	2.12
40-60	87,220	2.85
60-80	13,590	3.96

In a continuous reaction it is necessary to operate with a substantial quantity of recycle gas in order to remove the heat of reaction. This recycle gas strips the reactor of monomeric aldehyde so that the aldehyde concentration of the reactor seldom exceeds 1 to 2%. However, it can be seen from Table III that even at these low alde-

hyde concentrations, the preferential removal of one of isomers has a profound effect on the ratio of isomers formed.

Additional evidence for the effect of butal formation on the ratio of isomers formed is presented in the following examples run batchwise. In Example 8 which follows, the rate of reaction was 11.4 gram moles per liter of reaction space per hour and the ratio of normal to isobutyraldehyde formed was 2.6:1. In Example 9 the rate of reaction was 33.2 gram moles per liter of reaction space per hour and the ratio of normal to isobutyraldehyde formed was 1.8:1. From this data it can be seen that, if there is sufficient time for the butal formation, the greatest effect due to butal formation is realized.

EXAMPLE 8

One hundred and ninety grams butanol, 10 g. of water, and 20 g. of reduced oxo catalyst were charged to a 1-liter stainless steel autoclave and 2 gram moles of propylene were oxonated with carbon monoxide and hydrogen at 140-165° C. and 2,300-3,200 p. s. i. The rate of aldehyde production in this run was 11.4 gram moles per liter of reaction space per hour. The crude product was filtered and together with an equal volume of 1% sulfuric acid charged to a distillation column. Azeotropic distillation of the butyraldehydes gave a ratio of normal to isobutyraldehyde of 2.6:1.

EXAMPLE 9

In a second run employing the same charge as Example 8 plus a preactivation period wherein the catalyst was treated with carbon monoxide and hydrogen at 90° C. and 2500 p. s. i. for 30 minutes, the rate of butyraldehyde formation was 33.2 gram moles per liter of reaction space per hour. Distillation of the aldehyde formed gave a normal to isobutyraldehyde ratio of 1.8:1.

Still another method of directing isomer formation in the oxo process is to employ a lower aliphatic ketone as a solvent or reaction medium. The effect of a ketone solvent is shown in Example 10.

EXAMPLE 10

Eight grams of cobalt carbonyl dimer were dissolved in 200 g. of methyl ethyl ketone. The solution was charged to a 1-liter autoclave and 2 gram moles of butylene together with excess carbon monoxide and hydrogen were charged to the autoclave at 2,200-3,500 p. s. i. and 140-163° C. The reaction was complete in 16 minutes and the contents of the autoclave were blown off and condensed. The crude product, together with an equal volume of 1% sulfuric acid, was charged to a distillation column and fractionation gave 23 g. of isovaleraldehyde and 131 g. of normal valeraldehyde, or a ratio of normal valeraldehyde to isovaleraldehyde of 5.7:1.

From the above examples it can be seen that the invention is generally concerned with methods of operation wherein the ratio of normal to isovaleraldehyde formed in the oxonation of olefins can be controlled. It is specifically concerned with processes wherein the oxonation of olefins and olefinic compounds is carried out in the presence of optimum concentrations of aldehydes, acetals,

alcohols, and/or ketones. These examples are merely illustrative of the invention and are not to be interpreted in a limiting sense.

We claim:

- 5 1. The process of producing organic carbonyl compounds wherein the formation of isomers is directed by carrying out the reaction of an olefin or olefinic compound with carbon monoxide and hydrogen, in the presence of a catalyst selected from cobalt and iron in a form capable of catalyzing the oxo reaction, at temperatures ranging between about 40° and 200° C. and at a pressure between about 40 and 700 atmospheres wherein the reaction is carried out in the presence of a substantial added quantity of one of the isomeric aldehydes produced in the reaction, thereby directing the reaction to the formation of the other aldehyde isomer.
- 10 2. The process of claim 1 in which the source of isomeric aldehydes is selected from dimers and trimers of the aldehydes.
- 15 3. The process of producing organic carbonyl compounds which comprises reacting with carbon monoxide and oxygen in the presence of a catalyst selected from cobalt and iron in a form capable of catalyzing the oxo reaction, at a temperature ranging between 40-200° C. and at a pressure ranging from 40-700 atmospheres on an organic substance selected from the group which consists of aliphatic and cyclic olefins to produce a mixture of normal and isovaldehydes wherein the reaction is carried out in a solvent medium comprised of an added quantity of acetal of one of the isomeric aldehydes, thereby directing the reaction to the formation of the other isomeric aldehyde.
- 20 4. The process for producing butyraldehydes by reacting propylene with carbon monoxide and hydrogen in the presence of a catalyst selected from cobalt and iron in a form capable of catalyzing the oxo reaction, at a temperature ranging between 40-200° C. and at a pressure ranging between 40-700 atmospheres, wherein the reaction is carried out in the presence of an acetal of isobutyraldehyde, which in turn is a source of isobutyraldehyde via a replacement reaction with normal butyraldehyde and thus represses further formation of isobutyraldehyde.
- 25 5. The process for producing aldehydes by reacting an aliphatic olefinic hydrocarbon with carbon monoxide and hydrogen in the presence of a catalyst selected from cobalt and iron in a form capable of catalyzing the oxo reaction, at a temperature ranging between 40-200° C. and at a pressure ranging between 40-700 atmospheres to produce a mixture of normal and isovaldehydes, wherein the reaction is carried out in the presence of an acetal of one of the isomeric aldehydes, thereby directing the reaction to the formation of the other isomeric aldehyde.
